MINIATURE MULTIPLE UNIT VARIABLE RESISTOR

Karl W. Youngbeck and Henry J. Glueckstein,
Milwaukee, Wis., assignors to Globe-Union Inc.,
Milwaukee, Wis., a corporation of Delaware

Application October 6, 1948, Serial No. 53,118

5 Claims. (Cl. 201—55)

1

This invention relates to improvements in variable resistors, and particularly to miniature multiple unit variable resistors.

Units of this type are used for hearing aids, telephone equipment, and in other electronic circuits where smoothness of operation, compactness, and small size are required characteristics. Resistors of this type may be connected for tandem or dual (independent) operation. In either case the problem is to arrange and hold together the variable resistor units without using bulky or insecure fastening means and space-consuming couplings.

It is an object of this invention, therefore, to provide a miniature multiple unit variable resistor in which the units are secured together in coaxial arrangement in such fashion that a minimum of space is required by the resistor.

It is a further object of this invention to provide a dual control miniature multiple unit variable resistor in which the control knobs are so arranged and secured to the control shafts of respective units that the overall length of the unit is maintained at a minimum.

These objects are obtained by: coaxially arranging a plurality of variable resistor units having identical housings; providing one of the housings with radially projecting mounting brackets which are utilized both to secure and support the resistor on a chassis or the like and to fasten the units together; securing tie brackets to the housing of an adjacent unit; and interconnecting the tie brackets with the mounting brackets so as to hold the units as so arranged. To provide sufficient space for the inclusion of a connecting coupling between the shafts of adjacent units there is positioned between the units a spacer disc which also functions as a cover plate for the open end of one of the units. This disc is notched to accommodate the mounting brackets and permit a flush fit of the units. When the unit is assembled for dual control, an inner control knob is secured to the shaft of the outer unit by a knob-locking clip and an outer control knob is secured to a coupling shaft which operates this inner unit. This outer knob overlies and encloses projecting portions of the spaced arms on the knob-locking clip which hold the inner knob. In this way the space required to secure the knobs to the desired shafts is kept to a minimum and the appearance of the unit enhanced.

The novel features, which are considered characteristic of the invention, are set forth with particularity in the appended claims. The invention, itself, however, both as to its organization

2

and its method of operation, together with additional objects and advantages thereof, will best be understood from the following description of a specific embodiment when read in connection with the accompanying drawing, in which:

Fig. 1 is a perspective rear view of a tandem control miniature multiple unit variable resistor embodying the present invention;

Fig. 2 is an enlarged view partly in side elevation and partly in cross section of the variable resistor viewed in Fig. 1;

Fig. 3 is a fragmentary cross sectional view taken on the line 3—3 of Fig. 2;

Fig. 4 is a perspective view of the coupling for connecting the shafts of the variable resistor units;

Fig. 5 is a view partly in side elevation and partly in cross section of a dual control miniature multiple unit variable resistor embodying the present invention;

Fig. 6 is an enlarged sectional view taken on the line 6—6 of Fig. 5;

Fig. 7 is an enlarged sectional view taken on the line 7—7 of Fig. 5; and

Fig. 8 is a perspective view of the coupling shaft by which dual control of the resistor is obtained.

Referring to the drawings by reference numerals, there is viewed in Fig. 1 a tandem control miniature multiple unit variable resistor, generally designated 10. A dual control resistor 11 of this multiple unit type is viewed at Fig. 5. Both resistors consist of two variable resistor units having identical housings and substantially identical operating elements except for slight differences between the shafts of the front and rear units and between the shafts of the tandem and dual types. As herein used, front or forward will be toward the right, and rear or back will be toward the left as viewed in Figs. 2 and 5. Each resistor unit for both dual and tandem types comprises a housing 12 having a base or rear wall with a centrally mounted shaft holding bushing 14. Each housing also includes a peripheral side wall providing an opening at the front of the housing. The opening of the front unit is normally closed by a washer type cover 16 and the opening of the rear unit by a spacer disc 46. The construction of the resistor units is of conventional design. Each includes a flat strip type resistor resting against the inner face of the base connected thereto and to the outer terminals 18 and 20 by suitable rivets. A rotatable spring contact member 22 is mounted on the milled end of each of shafts 24, 24a, 26, and 26a and rotates therewith. This member has fingers

which ride on the resistor strip to vary the resistance when the shafts are rotated. There is also mounted on the milled end of these shafts a stop plate 28 which limits the rotation of the shafts to an angular amount of approximately two hundred and sixty degrees. The spring contact member 22 and stop plate 28 may be secured in place by staking over the end of the shaft. A middle terminal 30 riveted to the base of the housings 12 is connected by a pig-tail connector 32 to the spring contactor 22 so that the unit may be electrically connected in a desired circuit. The shaft with the spring contact member and stop plate in place are inserted in the bearing 14 from the inner end and held against axial movement by a C-ring 34. The shafts 24 and 26 are solid. However, the shaft 24 has a slot 36 in its forward end substantially parallel with the milled flats while the shaft 26 has a slot 38 in its rear end substantially at ninety degrees to the milled flats. These slots accommodate the flanges on coupling 40 (Figure 4) and thus the units are connected for tandem movement. Shaft 26 is somewhat longer than shaft 24 and has additional milled flats on its forward end on which control knob 42 is fixedly held by a hex screw 44. Rotation of knob 42 results in joint adjustment of both resistances of the resistor. It is necessary that the terminals 18, 20 and 30 of the front unit project radially from the rear of the housing to bring the units close together. However, the terminals 18, 20, and 30 for the rear unit may either project radially or axially from the rear of the housing, although the latter arrangement is more convenient when connecting wires to the terminals.

In order to rigidly secure and hold the rear unit to the rear of the front unit and to provide space for the coupler 40 there is inserted between the units a spacing disc 46 which may be made of plastic or other non-conductive material. The spacing disc 46 seats on the edges of the opening of the rear unit and also acts as a cover for the housing of that unit. The face of the disc has recesses 48 to accommodate the terminals 18, 20, and 30 and their rivets and recesses 49 to provide room for the mounting brackets 52 and 54. It also has a central aperture to provide operating space for the coupler 40. Around the edge of this aperture there is a recess 50 for accommodating the ridges on the rear surface of the base of the housings 12. The two units are arranged and held in coaxial position by mounting brackets 52 and 54 and tie brackets 56 and 58. The mounting brackets 52 and 54 project diametrically radially from the rear wall or base of the forward unit being held to the face thereof by rivets. The tie brackets 56 and 58 have body portions resting flat against and riveted to the base or rear wall of the rear unit and legs closely paralleling the sides of the rear housing and projecting forwardly into engagement with the mounting brackets 52 and 54. The ends of the legs project through slots in the mounting brackets and are staked or bent over as indicated at 60 to hold the legs to the mounting brackets. The legs may be secured by other means, such as soldering or welding, so long as the connection is made while the units are held tightly together. This manner of inter-connecting the units conserves the greatest amount of axial and diametrical space and is of considerable importance when it is considered that each unit has an overall diameter (exclusive of the knob terminals and mounting bracket and tie bracket) of only approximately .615 to .619 inch.

In the device shown in Figures 5 to 8, each of

the units is separately operated by its own control knob so that the multiple resistor has dual rather than tandem control. Each of the resistor units 12 is fastened together in the same manner as hereinbefore described for the tandem control unit. The main difference resides in the provision of a bore 62 in the rear unit shaft 24a and a bore 64 in the front unit shaft 26a. The shaft 26a also has an extension 66 provided with milled flats, which permit the knob-locking clip 68 to slide thereon, and a retaining groove 67. Before the rear unit is assembled to the front unit a coupling shaft 70 (see Figure 8) is inserted through the counter bore 64 so that its coupling end is at the rear end of the shaft 26a. The coupling head of this shaft interlocks with the slot 72 in the forward end of shaft 24a. To keep the dual control unit at a minimum length it is necessary to provide a compact manner for mounting the control knobs on their respective shafts. The inner knob 74 has an oblong recess which receives the milled extension 66 to cause the shaft 26a to be rotated therewith. The knob-locking clip 68 is first fitted over the extension 66 and then rotated ninety degrees to lock it in the groove 67, thus holding it against axial displacement. The knob-locking clip 68 has forwardly projecting arms 76 substantially normal to the plane of its body portion which fit through slots 78 in the knob 74; the knob being held on the arms 76 by bending over an outer corner 80 of the end of said arms. It is more satisfactory, although not necessary, to notch the arms 76 near the tips so that when the corners are bent, as shown in Figure 7, a sloping edge 82 will engage the outer edge of the slots 78 to stress the engagement between the knob 74 and the clip 68, thus firmly seating the extension 66 in the recess of the knob. When the knob 74 is fastened as heretofore described, a suitable cylindrical tool may be inserted in the bore 62 and the coupling shaft 70 urged forwardly by such tool so that its head is flush against the rear end of shaft 26a. While so held an outer knob 84 is fitted over the end of coupling shaft 70 and secured in place by the set screw and milled flat arrangement indicated at 85 and 88. It is preferable to place a thin shim between the knob 74 and the knob 84 during assembly which when removed will provide for sufficient clearance between these knobs. A recess in the rear of knob 84 provides clearance space for the ends of legs 76. Although only one embodiment of the invention is shown and described herein, it will be understood that this application is intended to cover such changes or modifications as come within the spirit of the invention or scope of the following claims.

We claim:

1. In a variable resistor having a plurality of variable resistor units mounted in identical coaxially arranged housings, the combination laterally projecting mounting brackets secured to one of said housings, said mounting brackets having slots for receiving the ends of the brackets and means by which said resistor may be mounted to a chassis or frame with tie brackets secured to an adjacent other one of said housings, said tie brackets having legs paralleling the sides of said last mentioned housing and ends projecting through said slots and staked against said mounting brackets whereby said housings are maintained in prearranged relationship.
2. In a variable resistor having a plurality of variable resistor units mounted in identical coax-

ially arranged housings, the combination of laterally projecting mounting brackets secured to the base of one of said housings, said mounting brackets having means by which said resistor may be mounted to a chassis or frame, with tie brackets secured to the base of an adjacent other one of said housings, said tie brackets having longitudinally extending legs paralleling the sides of the said last mentioned housing and ends secured to said mounting brackets to maintain said housings in prearranged relationship.

3. In a miniature multiple unit variable resistor having each unit enclosed in identical housings, the combination of laterally projecting mounting brackets secured to the base of a first housing, with a spacing disc forming a cover for an adjacent second housing and spacing said first and second housings, there being recesses in said spacing disc to accommodate said mounting brackets, and tie brackets secured to the base of the second housing and extending to and engaged with said mounting brackets.

4. In a miniature multiple unit variable resistor having coaxially arranged units operated by shafts, an inner knob for operating the shaft of a first unit, said knob being connected to the shaft of said first unit by a knob-locking clip consisting of a body mounted on the shaft between said resistor and said inner knob, said body having spaced arms projecting normally to the plane of the body, said inner knob having slots through which said arms project, said arms having a bent tip holding said knob on said arms, and an outer knob secured to the shaft of a second unit, said outer knob having a recess on its inner wall for accommodating and enclosing said bent tips.

5. In a miniature multiple unit variable resistor having coaxially arranged units, bored shafts for controlling said units severally rotatably mounted in each unit, an inner knob connected to the shaft of a first unit, a coupling shaft concentrically mounted within the bore of said last-named shaft, said coupling shaft having a coupling head at its inner end consisting of a flange extending radially of said shaft to limit the axial movement thereof, and a key extending outwardly of said flange, an outer knob mounted on the outer end of said coupling shaft, a slot in the bored shaft of a second unit for receiving said key to provide a driving connection between said coupling shaft and said bored shaft, the bore in the shaft of the second unit having an end opening permitting the insertion of a tool through such shaft to engage and outwardly axially urge said coupling shaft during the assembly of said outer knob.
